UNITED STATES PATENT OFFICE.

PHILIP D. PARSONS, OF PHILADELPHIA, PENNSYLVANIA, ASSIGNOR TO SCOTT PAPER COMPANY, A CORPORATION OF PENNSYLVANIA.

MACHINE FOR FOLDING AND SEVERING PAPER.

Application filed January 29, 1917. Serial No. 145,161.

To all whom it may concern:

Be it known that I, PHILIP D. PARSONS, a citizen of the United States, and resident of Philadelphia, county of Philadelphia, 5 and State of Pennsylvania, have invented an Improvement in Machines for Folding and Severing Paper, of which the following is a specification.

Increasing use of paper towels has resulted in the adoption of better means for dispensing the same, and one of the best means is a cabinet containing the paper towels ready cut and folded. My invention relates to improvements in paper towel 15 folding machines which prepare paper for use in such towel cabinets.

The object of my invention is to provide an improved paper towel folding machine capable of converting suitable paper supplied in web form, into cut and folded paper towels in counted batches and capable of operating in a reliable and efficient manner.

A further object of my invention is to provide an improved paper towel folding machine requiring a minimum of attendance; a machine which is practically continuous in its operation and in which the functions of feeding, folding, cutting and counting the paper towels are automatically 25 performed.

More specifically considering my invention, I provide a means adaptable for holding a roll of paper, a suitable power driven device capable of causing the paper web to be fed through the machine, means capable of folding the paper into the desired form, a device capable of cutting the folded paper into fixed predetermined lengths, and a means to deliver the folded papers of fixed 35 length (constituting towels) in counted batches.

My invention also consists of improvements hereinafter described whereby the above objects and results are attained, said 45 improvements comprising certain organization and combination of parts which are fully described hereinafter and more particularly defined in the claims.

For the purpose of illustrating my invention I have shown in the accompanying drawings the embodiment thereof which is at present preferred by me, since the same

is in form to give satisfactory and reliable results, but it is to be understood that the several instrumentalities of which my invention consists, can be variously arranged and organized and that my invention is not limited to the precise arrangement and organization of the instrumentalities herein shown and described.

Referring to the drawings:—Figs. 1, 2 and 3 should be considered together as showing a plan view of the machine in which Fig. 1 shows the left-hand end; Fig. 2 the center part, and Fig. 3 the right-hand end; 55 Figs. 4, 5 and 6 should be considered in a similar manner as showing in elevation the same machine shown in plan in Figs. 1, 2 and 3; Fig. 7 is a detail of the mechanism for delivering and counting the folded paper 60 towels; Fig. 8 is a plan view of the formers over which the paper is given its final folds; Fig. 9 is an edge view of the same; Fig. 10 is a cross section of the paper web when folded two ply; Fig. 11 is a cross section of the same when the flaps are folded into position to make the completed towel; Fig. 12 is a perspective view of one of the 65 completed paper towels; and Fig. 13 is a skeleton perspective view showing the general relation of the parts which finally act upon the folded paper web and sever it into 70 towel lengths.

The complete machine consists of means adapted for holding the roll of paper comprising a spindle and supporting frame, means capable of folding the paper into the desired form comprising formers and rolls, a suitable power driven device capable of causing the paper to be fed through 75 the machine comprising friction rolls, a device capable of cutting the folded paper into predetermined lengths comprising a revolving knife mechanism, and a means to deliver 80 the folded paper towels in assembled and 85 preferably counted batches comprising a conveyor belt and cam actuated counting mechanism.

The means for holding the roll of paper comprises a suitable spindle 2 which carries 90 the roll of paper 3, and a suitable frame 4 supporting the ends of said spindle 2 (Figs. 1 and 4). There is also provided a brake shoe 5 which bears against the circumfer- 95

ence of the roll and is fixed to the end of a 2
brake lever 7. The pressure with which the
brake shoe bears on the roll is adjusted by
means of the helical spring 8 secured at one
5 end to the brake lever 7 and at the other end
fastened over one of a plurality of hooks 9.
It is apparent that fastening the spring to
the upper hooks 9 will increase the spring
tension and consequently the frictional pres-
10 sure of the brake shoe on the roll. The ob-
ject of this adjustable braking device is to
retard the unrolling of the paper by just
that amount necessary to keep the paper web
taut. If the retardation of the roll of paper
15 be too great, it increases the power con-
sumed in driving the machine and may
even cause the paper web to break; if it be
too slight, the paper tends to unroll due to
the inertia of the roll and tends to impede
20 the folding device. For the purpose of fa-
cilitating the operation of placing a new
roll of paper in the machine, I have pro-
vided two levers 10 having a hook-shaped
25 socket portion 11 extending under the roll
spindle 2, said levers pivoted on pins 12, and
said pins affixed to frame 4 and acting as
guides for the slots 13 of said levers 10. It
will be seen that these levers 10 have a lon-
30 gitudinal adjustability of the length of the
slot 13 and as shown, are in their upper ver-
tical position as assumed just after lifting
the spindle 2 and paper roll into position to
be supported by the bearings 4^a. When the
35 machine is operating, the levers 10 normally
will be in their lower vertical position with
the pins 12 against the upper parts of the
slots 13.

The brake lever 7 has a projection 14 near
its pivotal or hinge point 15 capable of
40 receiving the dog 16, to keep the brake 5 out
of contact with the paper roll when apply-
ing a new roll of paper. The dog 16 has
a treadle lever 17 attached thereto whereby
45 pressure on the treadle disengages the dog
from the projection and permits the brake
to be applied to the paper roll.

To insert a new roll of paper, the empty
spindle is first lifted from the bearings 4^a.
The lever 7 is then thrown down so that the
50 dog 16 engages the projection 14 and thus
holds the lever in its lowest position. Then
levers 10 are swung to the left and lowered
until their upper ends reach the floor and
form inclined guides between which the
55 new roll of paper is rolled until the ends
of its spindle or shaft 2 thereof strikes said
guide portions of the levers and then the
levers 10 are raised and the spindle ends
caused to roll along the guide surfaces of
60 the levers and rest in the hook bearings 11
thereof. The levers are then raised further
into a vertical position as shown in Fig.
4, and the under curved part of the lower
65 socket portion of the levers seats in the verti-

cal position, and they in turn support the
spindle or shaft 2 for the roll of paper 3.
The levers 10 in seating in the bearings 4^a
slide upon the pins 12 through the medium
of the slots 13 before referred to, these slots 70
being sufficient in length to permit the levers
to be placed in or removed from the bear-
ings 4^a, as will be readily understood by
reference to Fig. 4. It will be noted that
when the levers 10 are in vertical position, 75
they are held in that position by the pins
12 and the seating capacity which they have
in the bearings 4^a. The treadle lever 17
is now pressed down, disengaging the dog
16 and allowing the brake lever 7 to rise 80
and the brake shoe 5 forced against the
paper roll under spring action. The paper
is now unrolled by hand and threaded
through the machine previously to applying
the power. 85

The means capable of folding the paper
into the desired form comprise a horizontal
guide roll 18 supported above a suitable
table 19. The paper feeds at full width
over this roller and then over an inverted 90
V-shaped folder comprising a cross bar 20
slightly V shaped and downwardly flaring
side plates 21 integral with the bar. In
passing over the cross bar 20 of the folder
and by reason of its shape, the paper may 95
receive a slight crease approximately at the
center which enables it to follow easily the
upper central edge 22 forming the union of
the side plates 21. At the delivery end 23
of the folder, the paper has been folded 100
once on a longitudinal seam and it is now
two-ply and in vertical position with the
fold at the top. A fold adjustment device
is here provided comprising two vertical
guide rods 24 mounted on a horizontal ex- 105
tension 25 carried by the said folder plates
21. The paper passes from the folder be-
tween said rods and guided thereby. A yoke
piece 26 is fastened to the table 19 and is
provided with oppositely directed adjust- 110
ing screws 27 between which the extension 25
is arranged, and by which its position and
the delivery end 23 of the folder may be ad-
justed. This adjustment is permitted by
reason of the fact that the folder is sup- 115
ported upon a pivot 28 about which it may
swing laterally. By this means the exact
position of the crease or fold in the paper
may be insured. This results in the paper
being folded over uniformly or unequally as 120
desired, that is to say, the line of the fold
may be made exactly in line with the cen-
ter of the paper, or not as desired. It is
desirable to have this first fold slightly
unequal (Fig. 10) in order that when the 125
paper is folded again to form the folds
108^a and 108^b (Fig. 11), the outer edges
will be true with one another because the
outer folds of the towel require more paper
than the inner folds and this is provided for 130

by the adjustment above described. This is also clearly indicated in Fig. 12, which shows a paper towel complete.

From the vertical guide rods 24 the folded paper web passes under a horizontal guide roller 29 which is arranged at an angle across the table 19 to bring the two-ply web into a horizontal plane. The ends of said guide roller are supported in adjustable bearings 30 such that the angularity and exact position of the roller may be adjusted to regulate the exact position of the longitudinal fold to cause a slight difference in widths of the layers or plies of the sheet when folded into two-ply (Fig. 10) to insure the free edges coming into alinement after the subsequent folding of the flaps 108^a and 108^b (Fig. 11) has been made. While the folder, first described, may be adjusted to position the middle fold, this latter is positively defined and fixed by a strong crease caused in passing under the roller 29; and by having one or the other end of this roller higher, the exact position of the crease can be varied to cause a greater or less difference in the widths of the two-ply layers for enabling the special flap fold 108^b to be made with the free edges in alinement, as described hereinafter. The bearings 30 have vertical shanks 30^a adjustably clamped in socket portions 30^b by the set screws 30^c.

Adjacent to the guide roller 29 is a transverse horizontal guide rod 31 set close to the table and beneath which the folded paper web passes. At this point the paper begins to receive its final or flap folds. This final folding is accomplished by drawing the paper through a former 32 having a loose die plate 33 around which the paper passes and over which the side portions are folded. This former comprises, in addition to the plate 33, a bottom plate 34 and two side flap folding plates 49 and 50 leaving a gap 52 between their adjacent edges. These plates 49 and 50 are bridged by a bar 51 (connected to plate 50) forming an abutment above plate 33 against which the rib 53 on said plate 33 abuts to hold it from being drawn along with the paper web. These side plates and bottom plate are fastened to the table 19 in any suitable manner, preferably detachable to permit change in formers when the relation and widths of the towel flaps are required to be changed.

The paper web, after passing from the oblique or diagonally arranged roller 29, is caused to have its edges (in act of folding side flaps) guided under rods 40 extending laterally from opposite sides of the web (Figs. 3 and 6), and these are held by vertically adjustable brackets 42 having slots 34^a and clamping screws 35.

The suitable power driven device capable of causing the paper to feed through the

machine comprises the friction rolls 43, 54, 69 and 55. The rolls 55 operate as a pair and are geared together at 55^a. As the paper travels along the table 19, it passes between embossing rolls 41 and 43. The roll 41 is 70 carried by spindle 56 in bearing 57 and is positively rotated. The roll 43 is fixed on a shaft 58 having at one end the bevel gear 59 driven by bevel gear 60. The said gear 60 is secured to shaft 61 carried in suitable 75 bearings 62 and 63. Shaft 61 also carries a bevel gear 64 driven by bevel gear 65, the latter being mounted on the main shaft 66 which is driven by pulley 67. In the present instance I have shown an electric motor 68 80 driving this pulley by a belt 68^a. Thus the roll 43 is driven to feed the paper through the folder devices of the machine. Fixed to the main shaft 66 is a friction roll 54. The folded paper passes between this roll 85 and a free running pressure roll 69 located directly above it and carried by shaft 70 and suitable bearings 71. The roll 69 is caused to bear on the folded paper with considerable pressure by means of the weight 72 90 adjustably secured to the lever arm 73 by a locking device 74. The lever arm 73 passes through a yoke 75 and bears on its upper edge at the far end against a fulcrum 76. The yoke 75 transmits the pressure due to 95 the lever 73 and weight 72 to the roll 69 through suitable links 77. Thus the folded paper is held against roll 54 by roll 69 and is positively fed by said roll 54. The folded paper is thus flattened and drawn along by 100 the friction rolls 55. The lower of these friction rolls 55 is mounted on a shaft 78^a having a sprocket 79 driven by a chain 80 from a sprocket 81 on the main shaft 66. The shaft 78^a is geared to the shaft 78 of 105 the upper of the friction rolls 55. After the folded paper has been cut, (as below described), it is still in contact with rolls 55 and is delivered by them into a suitable compartment 81.

The device capable of cutting the folded paper into fixed predetermined lengths consists of a knife 82 fastened to a large disc 83 and extending radially. The said disc is slidably mounted on a shaft 84 driven by a 110 bevel gear 85 from the bevel gear 65 on the main shaft 66. The other or fixed cutting edge for the knife is placed beneath the paper as at 86. To cause the knife to rotate true to cooperate with the fixed cutter 86, 120 the large disc 83 is pressed against a large flat surface on the main frame by a spring 87 on the shaft 84. This spring 87 bears at one end against the washer and nut 88 of the shaft and at the other end against a suitable hub 125 on the disc. This disc is suitably mounted on shaft 84 so as to permit of slight movement along the shaft while at the same time being driven by it.

It will be readily apparent that by chang- 120

ing the ratio of the gearing driving the revolving knife, towels of various lengths can be cut, but that when once the gearing is installed, the positive drive of the knife from the same source of power which feeds the paper, insures that all the towels will be exactly of the same length.

The means to deliver the folded papers of fixed length designated towels in counted batches, comprise the compartment 81^a in which the towels are delivered from the friction rolls 55. The end of the towel strikes a curved metal guide 89 and is forced down on a transversely moving conveyor belt 90. The guide 89 is mounted on a hinge 91 so that when desired, it may be swung back for inspection of the interior of compartment 81. Within this said compartment and near the end adjacent to the friction rolls 55 is located a curved strip of metal 92 designated a beater. This is mounted on a shaft 93 having a sprocket wheel 94 which is driven by a chain 95 from sprocket wheel 96 on shaft 78 of the friction rolls 55. Thus the beater is caused to make one revolution for each towel cut, and forces the forward end of the towel down on conveyor belt 90. The said conveyor belt passes over a free running upper guide pulley 97 and a driven lower pulley 98 (Fig. 7). The lower pulley is driven by a sprocket wheel 99 fixed on pulley shaft 100 by a chain 101 and sprocket wheel 102. This latter is mounted on a shaft 103 carrying a worm gear 104 driven by a worm 105 on the main shaft 66.

The devices thus described will deliver the folded towels in a successive manner on the conveyor belt 90, said towels overlapping owing to the travel of the belt. To keep the edges of the towels in alignment upon the belt, suitable guide plates 106 are provided.

To divide the towels into counted batches, a vertical stop gate 107 is caused to descend into the moving batch of towels 108, whereby the towels in the compartment 81 are dammed or held back momentarily to provide a space between the batches of towels 108 at regular predetermined intervals. The said gate 107 is mounted on a vertical pin 109 carried by a suitably formed push rod 110. The lower end of this push rod rests on a lever 111 pivoted at 112. The lever 111 is held by a spring 113 against a cam 114, mounted on shaft 103, said cam having a recess 115 formed in its circumference. When the lever 111 is pulled into recess 115 by spring 113, the push rod 110 is allowed to descend vertically and consequently the stop gate 107 descends at the same time. The batch of towels behind stop gate 107 of necessity are dammed or come to rest, while those ahead are fed forward on conveyor belt 90. When the cam has been rotated sufficiently, the lever 111 moves out

of recess 115 and the push rod 110 and stop gate 107 are caused to rise again. The batch of towels then continue to travel forward on conveyor belt 90 but with a space between the towels which were caught by the stop gate and those which went forward beyond it. It will be apparent that the action of the stop gate occurs at each rotation of the cam 114 which is positively driven from the main shaft 66 through shaft 103. Hence the batches into which the towels are divided will comprise a definite number of towels depending on the ratio of gearing between the main shaft 66 and cam shaft 103.

In operation, after the roll of paper is secured as already described, the paper is threaded by hand over guide roll 18 through the folder 21 and vertical guide rods 24, under roller 29 and guide rod 31, and under guide rods 40. It is then passed between rolls 41 and 43, then folded over the loose former plate 33 and through the former, and into the feed rolls 54 and 69. The motor 68 is then put in motion. This rotates the pulley 67 and in turn the friction feed rolls 43 and 54. In consequence the paper feeds through in folded form and is received by the tension and feed rolls 55; then the knife 82 cuts off towels of the desired length. The tension maintained upon the paper between the rolls 55 and rolls 54, 69, will insure the revolving knife severing the paper with a clean cut at a point between said sets of rolls. The towels feed forward on the conveyor belt 90 as before described, and the operator gathers up the counted batches as they are delivered by the said belt in conjunction with the stop gate 107, and places them in separate bands or cases.

In Fig. 10, is shown the folded web after leaving the rollers 29 and 31 and in which it will be noted that the upper ply is of less width than the lower ply. In Fig. 11 the flaps are folded over by the former 33, etc., and it will be noted that in this case the free edges of the paper plies are in vertical alignment, the difference in the bends having readjusted the plies. Had the plies been of the same width in Fig. 10, the upper free edges in Fig. 11 would have been considerably to the left of the free edge of the under flap and hence undesirable.

It is also to be understood that while I have described my machine for the manufacture of paper towels, the folded papers may be utilized as napkins or for other purposes, if so desired.

It will be apparent that by changing the former plate 33 with its accompanying parts to similar devices of slightly different form, the paper towels may be folded in substantially any desired manner as to width of orlapping of the flaps. Changing the former

may, however, necessitate some adjustment of the feed and folding devices such as guide roll 29, guide rods 40, and the embossing roll 41. For instance where a towel is folded with uneven folds it may be necessary to adjust one rod 40 higher than the opposite rod 40, and to move the embossing roll 41 along its shaft 56. It should also be noted that whereas the machine is shown as 10 motor driven, yet it could as easily be driven from any other source of power, belted or geared to the main shaft 66.

From the foregoing, it will be seen that I have invented a machine capable of converting suitable paper supplied in roll form into cut and folded paper towels in counted batches. The parts of which the machine is composed are easily accessible and are capable of strong mechanical design which 20 insures their reliable operation. The power required is utilized in overcoming the friction of the paper against the folders, formers and guides and in overcoming the frictional losses in the driving mechanism. The 25 loss due to the friction of the paper may be reduced to a minimum by adjustment of the paper tension, adjustment of the guides and of the formers through the means described. The frictional losses in the drive have been 30 kept low by simple design. It will also be noted that when once the machine has been started, further operation is continuous and automatic and the operator has no further duty save that of lifting out the counted 35 batches of folded towels.

It will now be apparent that I have devised a novel and useful construction which embodies the features of advantage enumerated as desirable in the statement of the 40 invention and the above description, and while I have in the present instance shown and described the preferred embodiment thereof which is best suited to give satisfactory and reliable results in practice, it 45 is to be understood that the same is susceptible of modification in various particulars without departing from the spirit or scope of the invention or sacrificing any of its advantages.

50 No claim is made in this application to the mechanism for bunching of the several paper articles produced, the same constituting matter for a divisional application.

Having now described my invention, what 55 I claim as new and desire to secure by Letters Patent, is:—

1. In a machine of the character stated, the combination of means for folding a web of paper longitudinally to form a two-ply 60 web, adjustable means at the delivery end of the folding means for adjusting the folding means transversely, whereby the line of the fold may be adjusted, former means for again folding the two-ply web longitudinally upon two parallel lines to provide a

body and oppositely directed lateral flap portions, and means for severing the folded web into short lengths to form articles.

2. In a machine of the character stated, the combination of means for folding a web 70 of paper longitudinally to form a two-ply web, adjustable means for controlling the folding to cause one ply to be wider than the other by a predetermined amount, former means for folding the two-ply web 75 longitudinally upon two parallel lines to provide a body and lateral flap portions, means for severing the folded web into short lengths to form articles, and means for assembling the articles so produced into 80 batches of equal numbers.

3. In a machine of the character stated, the combination of means for folding a web of paper longitudinally to form a two-ply web, adjustable means for controlling the 85 folding to cause one ply to be wider than the other by a predetermined amount, former means for folding the two-ply web longitudinally upon two parallel lines to provide a body and lateral flap portions, means for 90 severing the folded web into short lengths to form articles, a laterally moving apron upon which the severed paper articles are delivered, means for directing the articles upon the apron so that they overlap each 95 other laterally, and means for arresting the conveyance of the articles upon the apron at intervals of time.

4. In a machine of the character stated, the combination of means for folding a web 100 of paper longitudinally into a two-ply web with a second folding means comprising a former having oppositely directed folding guides by which the two-ply web is provided with oppositely directed flaps, two 105 pair of feed rolls through which the folded paper web is successively fed, a rotating shaft having a radial cutter blade arranged to revolve intermediately of the two pair of feed rolls in a plane parallel to their axes to 110 sever the folded web into short lengths to form articles, connecting means for causing the cutter and feed rolls to move at definite relative speeds, and means to receive the severed paper articles and feed them successively laterally out of the path of the 115 following travelling articles.

5. In a machine of the character stated, the combination of means for folding a web of paper longitudinally into multi-ply with 120 oppositely directed flaps, two pair of feed rolls through which the multi-ply paper web is successively fed, a rotating shaft having a radial cutter blade arranged to revolve intermediately of the two pair of feed 125 rolls to sever the web into short lengths to form articles, connecting means for causing the cutter and feed rolls to move at definite relative speeds, and means to receive the severed paper articles and feed them suc- 130

cessively laterally out of the path of traveling multi-ply web, comprising a laterally traveling apron, a rotating beater to depress the end of the article toward the apron, a 5 device for holding the paper articles to the apron and in overlapping relation to each other.

6. In a machine of the character stated, the combination of means for folding a web 10 of paper longitudinally into multi-ply with oppositely directed flaps, two pair of feed rolls through which the multi-ply paper web is successively fed, a rotating shaft having a radial cutter blade arranged to revolve intermediately of the two pair of feed rolls to sever the web into short lengths to form articles, connecting means for causing the cutter and feed rolls to move at definite relative speeds, and means for holding the 15 cutter up to its work consisting of a large disc rotating with the shaft but longitudinally movable upon it and upon which the radial cutter is secured, a flat surface on the frame of the machine upon which the disc 20 revolves, and spring devices on the shaft for constantly pressing the disc against the flat surface.

7. In a machine of the character stated, the combination of means for folding a web 25 of paper longitudinally in multi-ply, a pair of feed rolls for the folded paper, power means to rotate the lower roll of the pair, means for permitting raising and lowering the upper roll of the pair, weighted means 30 for forcing the upper roll toward the lower driven roll, a second pair of feed rolls, a radial cutter movable in a plane between the two pairs of rolls and parallel to their axes, for severing the web to form articles of substantial uniform lengths, means for receiving 35 and assembling the articles produced by severing the multi-ply web of paper.

8. In a machine of the character stated, a support for a roll of paper, combined with 40 a folder for folding the paper longitudinally into a two-ply web, an obliquely arranged roller under which the two-ply web is drawn, former means for folding the sides of the two-ply web toward each other to 45 form oppositely directed flaps, means to sever the prepared web into articles of short lengths, and means for adjusting the oblique roller to vary the position of the middle fold of the web when folded into two-ply.

55 9. In a machine of the character stated, a support for a roll of paper, combined with a folder for folding the paper longitudinally into a two-ply web, an obliquely arranged roller under which the two-ply 50 web is drawn, former means for folding the sides of the two-ply web toward each other to 55 form oppositely directed flaps, means to sever the prepared web into articles of short

length, and means for adjusting the folder laterally at its delivery end to vary the position of the middle fold of the web. 65

10. In a machine of the character stated, the combination of a support for a paper roll, a folder for folding the web into a two-ply web consisting of a transverse guide, a 70 pivoted inverted V-shaped folder substantially horizontal at one end and vertical at the other, two parallel vertical rods close together near to the vertical end of the folder and to the rear or delivery side of the pivot 75 and folder, means for adjusting the vertical end of the folder and its rods transversely, a horizontal guide roller arranged obliquely to the line of travel of the paper web adjacent to the lower ends of the vertical rods of the folder for receiving and guiding the folded web horizontally, and means for receiving the folded web and severing it into lengths to form separate articles. 80

11. In a machine of the character stated, means for feeding a web of paper longitudinally and folding it along its length to provide side flaps, combined with means for embossing the middle portion of the paper 90 web between the flaps while being formed with suitable characters at intervals along the length of the web, means for severing the folded web at intervals in its length, and connecting means between the severing 95 means and embossing means whereby the severing means is caused to sever the web at points intermediate of the parts which have been embossed to form separate embossed articles. 100

12. In a machine of the character stated, means for feeding a web of paper longitudinally and folding it along its length to provide side flaps, combined with means for embossing the middle portion of the paper 105 web between the flaps while being formed with suitable characters at intervals along the length of the web, means for severing the folded web at intervals in its length, connecting means between the severing 110 means and embossing means whereby the severing means is caused to sever the web at points intermediate of the parts which have been embossed to form separate embossed articles, and means for receiving and 115 assembling the successively formed embossed articles so that the embossed surfaces are located at the same sides of the assembled articles.

In testimony of which invention, I here- 120 unto set my hand.

PHILIP D. PARSONS.
